UNITED STATES PATENT OFFICE.

MARK E. FERNALD, OF SAUGUS, MASSACHUSETTS, ASSIGNOR TO C. C. BLAKE, INCORPORATED, OF BOSTON, MASSACHUSETTS, A CORPORATION OF NEW YORK.

MACHINE FOR MAKING CASTING-PATTERNS.

1,278,898.

Specification of Letters Patent. Patented Sept. 17, 1918.

Application filed October 27, 1914, Serial No. 868,921. Renewed February 14, 1918. Serial No. 217,254.

To all whom it may concern:

Be it known that I, MARK E. FERNALD, a citizen of the United States, residing at Saugus, in the county of Essex and State 5 of Massachusetts, have invented a new and useful Improvement in Machines for Making Casting-Patterns, of which the following is a specification.

The present invention relates to machines 10 for making flanged articles, and more particularly, to a machine for making casting patterns which determine the form of the leaders used in automatic shoe machines.

It has been proposed to perform the various 15 operations in the manufacture of shoes automatically. In one system of automatic shoe machines the transfer of the point of operation of the tool along the work is controlled by a leader upon which the work 20 supporting jack is mounted. These leaders usually comprise a body portion having the same form on one face as the sole of the shoe mounted upon the jack and a flange on the edge of the body portion which is usually 25 provided with teeth for engagement with a driving pinion. The flange also acts as a guide for swinging the jack laterally to permit the tool to traverse the reverse curves of the work. One of the principal objections 30 to the use of these automatic machines is the cost of producing these leaders which vary in size and shape with the various sizes and styles of soles intended to be incorporated into a shoe. The principal reason 35 for the high cost of these leaders is that heretofore it has been necessary for a skilled pattern maker to make the pattern for casting the leader. I propose to eliminate the necessity for the employment of a pattern 40 maker by producing the casting patterns for the leaders mechanically. I believe that I am the first to have conceived the idea for the mechanical production of casting patterns and to have devised operative mechanism 45 for carrying such idea into practice.

The object of the present invention is to produce a machine for making flanged articles such, for instance, as the casting patterns which determine the form of the leaders employed in automatic shoe machines.

To the accomplishment of this object the features of the invention relate to certain devices, combinations and arrangements of parts hereinafter described and then set

forth broadly and in detail in the appended 55 claims which possess advantages readily apparent to those skilled in the art.

The various features of the present invention will be readily understood from an inspection of the accompanying drawings 60 showing the best form of the invention at present known to the inventor, in which:

Figure 1 is a front elevation of a machine 65 for making casting patterns;

Fig. 2 is a plan;

Fig. 3 is an enlarged detail in front elevation, partly in section, showing the actuation of the feed accelerator when the point of operation of the operating means is transferred around the ends of the blank;

Fig. 4 is a detail in plan, partly in section, of the roll carrier, its support, and the feed accelerator;

Fig. 5 is a sectional plan on the line 5—5, 70 Fig. 1;

Fig. 6 is an exaggerated lateral section of the pattern made by the machine; and

Fig. 7 is a detail, partly in section, showing the mechanism for imparting a draft to the pattern.

Describing now in general terms my novel method of making casting patterns which determine the form of the leaders employed in automatic shoe machines the first step consists in the production of the blank for 85 the foundation of the pattern. As well known to those skilled in the art it is necessary in making a casting pattern to allow for the shrinkage in the casting. Furthermore in making a leader for a shoe machine it is necessary to allow for the "spring" of the last upon which the sole to be incorporated into a shoe is secured. To produce a sole-shaped blank having the shrinkage of cast iron and the spring of the 90 last measurements accounted for I mount the sole upon a last and cause a feeler operatively connected to a pencil to travel around the peripheral edge of the sole on the last. Interposed in the connections between the 100 feeler and pencil is a differential mechanism which enlarges, by the amount of the shrinkage of an iron casting, the movements imparted to the pencil by the feeler. By this means a sole-shaped area is traced having 105 the shrinkage of cast iron and the spring of the last incorporated therein. With this sole-shaped area as a guide a flat wooden

blank is made having the same size and shape. This sole-shaped blank is then inserted into my novel machine which is provided with a rotatable support for the blank, 5 devices for supporting, guiding and feeding a strip of material, such as paper, and a pair of rolls for attaching the paper to the peripheral edge of the blank and winding the paper in layers thereon to build the 10 guiding flange. The rolls are mounted on a carrier which tips automatically as the point of operation of the rolls is transferred around the reverse curves of the blank to maintain the rolls substantially normal to 15 the point of operation. This carrier is mounted on a swinging support which swings automatically during the rotation of the blank to permit the rolls to travel around the toe and heel portions of the blank 20 and reach the shank portions thereof. The machine is also provided with a feed accelerator which imparts an additional pull upon the supply end of the paper so that the paper may be attached to the shank portions 25 of the blank while the paper is free from tension. After the pattern is completed by this machine the draft necessary for the removal of the pattern from the sand is imparted to the pattern by a second 30 machine which is provided with a series of rolls which simultaneously support, guide, feed and operate automatically upon the pattern to impart the draft thereto and remove any roughness on the top and bottom 35 faces of the flange. The pattern is then provided with a coat of shellac.

In the illustrated embodiment of the invention a sole-shaped blank 1, (Figs. 1, 3 and 5), provided with a pair of holes 2, 40 (Fig. 5), is slipped upon a pair of pins 3 carried by a plate 4 which is pinned to a horizontal shaft 5 journaled in a vertical plate 6, (Fig. 1), of the machine frame. The shaft 5 is driven during the operation 45 of the machine to rotate the blank in a contra-clockwise direction from a countershaft 8, (Figs. 1 and 2), one end of which is journaled in the plate 6 and the other end of which is journaled in a bracket 9 carried by 50 the frame. The countershaft 8 carries a gear 10 which meshes with a gear 11 carried by the shaft 5. The countershaft 8 is driven from some suitable source of power through a bevel gear 12, (Fig. 2), on the shaft which 55 meshes with a bevel gear 18 carried by a vertical shaft 14. To permit the shaft 5 to be rotated manually by a hand wheel 15, (Figs. 2 and 5), pinned thereto the gear 10 is formed on a clutch sleeve 16 (Fig. 2), 60 which is driven from the shaft 8 through a clutch spline 17 carried thereby. The sleeve 16 and spline 17 are disengaged by a lever 18 having an operating handle 19 at one end and connected at its other end to a post 20 65 which is loosely mounted in a vertical bear-

ing 21 formed on the bracket 9. The spline 17 and lever 18 are connected by a semi-circular shoe 22, pivotally mounted on the lever 18, which travels in a cylindrical slot formed in the spline 17.

In order to clamp the blank upon the driving plate 4 a bracket 7, (Figs. 1, 2 and 5), carries a longitudinally movable post 23 upon which is mounted a rotatable plate 24, (Fig. 5), provided with a pair of holes for fitting over the pins 3 which project from the plate 4 through the holes in the blank. The plate 24 is held in clamping position by a spring 25, (Figs. 1 and 5), one end of which is connected to the plate 6 and the other end of which is connected to a lever 26 pivoted at its lower end to an arm 27 projecting from the bracket 7. Intermediate its ends the lever 26 is pinned between the arms 28 of a slot formed in the end of the post 23. To permit the unclamping of the blank and the locking of the plate 24 in an inoperative position the lever 26 is provided with an operating handle 29 and a dog 30, pivoted upon the lever 26, and arranged to snap behind the bearing for the post 23 when the post is moved by the operative to withdraw the plate 24 from the blank.

Before the blank is rotated one end of a strip of tacky paper is attached to the edge of the blank. A pair of tools is then brought down upon the attached paper one of which guides or lays the paper in position upon the edge of the blank during the rotation of the blank and the other one of which fixes or sets the tacky paper in a permanent position. The paper laying tool comprises a flanged roll 32, (Figs. 1 and 3), which is journaled in a roll carrier 33 centrally pivoted on a stud bolt 34 secured to a supporting arm 35 which is pivoted at 36 to the machine frame. The roll carrier also carries the fixing tool which comprises a roll 37. The rolls are normally held away from the blank to permit the initial attachment of the paper thereto by a spring-actuated pivoted dog 38, (Fig. 1), carried by the arm 35 and arranged to engage a lug 39 carried by a curved guide 40, secured to the plate 6, the arms of which loosely embrace the arm 35.

The paper for the blank may be presented thereto in any suitable manner found desirable or expedient. In the illustrated embodiment of the invention the strip of paper, provided on one face with a normally non-adhesive coating, is carried by the machine in the form of a roll 41 the usual wooden core of which rotates freely on the hub of a stationary reel, (partially shown in Fig. 1). The strip of paper from the roll is led through an opening (not shown) in the machine frame, over an abutment 43, formed on the cover of a water tank 44, and then over a roll 45, (Fig. 1). The roll 45 is mounted on a shaft 46 one end of which is journaled

in bearings formed on the cover of the water tank 44 and the other end of which is journaled in bearings formed in the plate 6, (Fig. 2).

5 In order to render the coated face of the paper tacky the roll 45 is provided with a felt rim 47 which, as it passes beneath the surface 48 of the water in the tank 44, becomes saturated with sufficient moisture to 10 thoroughly wet the coated face of the paper when the paper is pressed against the felt rim. The paper is pressed against the felt rim 47 by a second roll 49 mounted on a shaft 50 journaled in the legs of a bifurcated arm 51 which is pivoted at 52 on the plate 6, (Fig. 1). A finger 52a depending from the arm 51 insures the contact of a substantial length of paper with the roll 45. The roll 49 is normally pressed against the 20 paper on the roll 45 by a coiled spring 53 one end of which is connected to the arm 51 and the other end of which is connected to the machine frame. The shafts 46 and 50 carry gears 54 and 55 respectively normally 25 intermeshed so that, as the paper is fed by the rotation of the blank to which it is attached, the rolls will rotate together.

In order to separate the rolls when the operating tools are held out of their operating 30 position so as to permit the ready introduction of the paper between them the arm 35 carries a pin 56, (Fig. 1), which, as the arm is being elevated to latch the dog 38 on the lug 39, contacts with an extension 57 of one 35 of the legs of the bifurcated arm 51 thereby separating the rolls 45 and 49 and disconnecting the gears 54 and 55.

After the paper has been rendered tacky by the moistening apparatus the paper is led 40 over the roll 49 to bring its tacky face uppermost and is then led over a roll 58 and between a pair of pins 59 mounted on a plate 60, (Fig. 1). The plate 60 normally rests at one end upon a pin 61 carried by the arm 45 35, (Fig. 1), and at its other end is bifurcated (Fig. 4) so that it may straddle the roll 37 and rest upon the upper face of the roll carrier 33. Connected to the rear of the arms of the bifurcated plate 60 is a pair of 50 lugs 62 by means of which the plate 60 is pivoted upon the stud bolt 34. The paper is then led, between the roll 32 and a bridge 63, (Fig. 4), on the roll carrier 33, to the point of operation at which point one end of 55 the tacky paper is attached to the blank.

After one end of the paper has been initially attached to the edge of the blank and the operating tools depressed to engage the attached paper the machine is thrown 60 into operation to rotate the blank to transfer the point of operation of the tools around the blank and draw a fresh supply of paper from the roll 41. During the transfer of the point of operation of the tools around 65 the blank the roll carrier 33 automatically

tips on the bolt 34 to maintain the tools substantially normal to the point of operation as illustrated in Figs. 1 and 3. As the blank being operated upon is sole-shaped there is a tendency for the paper to "drum-head" 70 across the shank portions of the blank owing to the tension placed upon the paper by the rotation of the blank. To overcome this tendency the roll carrier 33 as it tips to maintain the rolls substantially normal to 75 the point of operation at the toe and heel portions of the blank actuates the plate 60 in the manner illustrated in Fig. 3 to pull upon the supply end of the paper so as to produce slack in the paper and thus enable 80 the rolls to attach the paper to the shank portions of the blank while the paper is free from tension, (Fig. 1). The plate 60 returns, under the influence of gravity, to its original position as soon as the carrier tips 85 in the opposite direction during the transfer of the rolls along the shank portions of the blank, (Fig. 1). The plate 60 is herein called a feed accelerator as it accelerates the feed of the strip due to the rotation of the 90 blank.

During the transfer of the point of operation of the tools around the blank the arm 35 which supports the roll carrier 33 swings on its pivot 36 to permit the rolls to travel 95 around the ends of the blank and reach the shank portions thereof. As illustrated in Fig. 1 the axis of the rotating blank 1 and the axis of the carrier 33 are located at equal distances from the axis of the support 35. This 100 construction permits the rolls to rise and fall under the influence of the rotating blank without danger of binding or producing excessive pressure as they reach the toe and heel portions of the blank. It will 105 also be seen from an inspection of Fig. 1 that the journal for the roll 32 is located a greater distance from the axis of the carrier 33 than the journal for the roll 37. By locating the journals for the rolls 32 and 110 37 at different distances from the axis of the tipping carrier in the manner described most of the weight of the arm 35 and its supported parts is transmitted through the roll 37 to the work. This manner of mounting the 115 rolls 32 and 37 insures the operation of the roll 32 under a light pressure to lay the paper in position and the operation of the roll 37 under a heavy pressure to fix the paper laid by the roll 32. 120

The blank is rotated until a flange of the desired thickness is built upon the edge of the blank at which time the supply end of the strip of paper is severed and the pattern removed from the machine. This pattern is illustrated (greatly exaggerated) in section in Fig. 6. As shown it consists of a body portion 64 comprising the sole-shaped blank and a laminated flange 65 which has been built upon the blank by winding a 125

strip of paper in layers around the peripheral edge of the blank.

In order to impart the draft to the pattern and smooth the irregularities on the top and bottom faces of the flange the pattern is passed through a machine provided with a series of rolls which support, guide, feed and operate automatically upon the pattern as it passes through the machine. As shown 10 in Fig. 7 these rolls comprise a pair of rolls 66 and 67 which engage the top and bottom faces of the body portion of the pattern respectively and which are also constructed and arranged to engage the inner faces of 15 the flange and impart the draft thereto, a pair of rolls 68 and 69 which engage the top and bottom faces of the flange respectively and smooth the irregularities thereon, and a fifth roll 70 which engages the outer face 20 of the flange and imparts the draft thereto.

While the invention has been illustrated and described as being particularly useful in connection with a machine for making casting patterns it will be apparent to those skilled in other arts that the general organization of the machine, together with various features of the mechanism by which the parts are operated, are applicable to machines for making other kinds of flanged 25 articles.

It will also be understood that, while it is preferred to employ the specific construction and arrangement of the parts shown and described, this construction and arrangement is not essential, nor is the conjoint use of all the features of the invention essential, except so far as specified in the appended claims, and it may be varied or modified without departing from the 30 broader features of the invention.

What is claimed as new is:—

1. A machine for making flanged articles, having, in combination, devices for supporting, guiding and feeding a strip of material, 45 and means for attaching the material to the edge of a flat blank to form a flange thereon, substantially as described.

2. A machine for making flanged articles, having, in combination, devices for supporting, guiding and feeding a strip of material, means for laying the material upon the edge of a flat blank, and means for fixing the material laid upon the blank to form a flange thereon, substantially as described.

3. A machine for making flanged articles, having, in combination, devices for supporting, guiding and feeding a strip of material, and successively operating devices for laying and fixing the material upon the edge of a flat blank, substantially as described.

4. A machine for making flanged articles, having, in combination, means for depositing material upon the edge of a flat blank, and means for fixing the material deposited

upon the blank to form a flange thereon, 65 substantially as described.

5. A machine for making flanged articles, having, in combination, a tool for depositing material upon the edge of a flat blank, and a second tool for fixing the material deposited upon the blank to form a flange thereon, 70 substantially as described.

6. A machine for making flanged articles, having, in combination, a roll for laying a strip of material upon the edge of a flat 75 blank, and a second roll for fixing the material laid upon the blank to form a flange thereon, substantially as described.

7. A machine for making flanged articles, having, in combination, a flanged roll for laying a strip of material upon the edge of a flat blank, and a second roll for fixing the material laid upon the blank to form a flange thereon, substantially as described.

8. A machine for making flanged articles, having, in combination, a support for a strip of material, means for rendering the material tacky, and means for depositing the tacky material upon the edge of a blank to form a flange thereon, substantially as described.

9. A machine for making flanged articles, having, in combination, a support for a strip of material having a normally non-adhesive coating thereon, means for rendering the material tacky, mechanism for depositing the tacky material upon the edge of a blank to form a flange thereon, and means for guiding the tacky material from the first named means to said mechanism, substantially as 95 described.

10. A machine for making flanged articles, having, in combination, a support for a strip of material having a normally non-adhesive coating thereon, a moistening apparatus for rendering the coating tacky, and mechanism for depositing and attaching the tacky material to the edge of a blank to form a flange thereon, substantially as described.

11. A machine for making casting patterns, having, in combination, a blank support, and means for building a flange on the edge of the blank, substantially as described.

12. A machine for making casting patterns, having, in combination, a blank support, operating means for building a flange on the edge of the blank, and means for relatively actuating the operating means and blank to transfer the point of operation of the operating means around the blank, 115 substantially as described.

13. A machine for making casting patterns, having, in combination, a blank support, means for building a flange on the edge of the blank, and mechanism for relatively moving the operating means and support to maintain them in proper relation as the point of operation of the operating 120 125

means is transferred around the blank, substantially as described.

14. A machine for making casting patterns, having, in combination, means for building a flange on the edge of the blank, devices for supporting and presenting the blank to the operating means, feeding means, and mechanism for changing the relative position of the blank and operating means and coöperating with the feed to present the blank properly to the operating means as its point of operation is transferred around the blank, substantially as described.

15. A machine for making casting patterns, having, in combination, means for building a flange on the edge of a blank, devices for supporting and presenting the blank to the operating means, means for relatively actuating the operating means and blank to transfer the point of operation of the operating means around the blank, and means for relatively tipping the operating means and blank during the transfer of the point of operation of the operating means around the blank to maintain the operating means substantially normal to the blank, substantially as described.

16. A machine for making casting patterns, having, in combination, means for building a flange on the edge of a blank, devices for supporting and presenting the blank to the operating means, means for relatively actuating the operating means and blank to transfer the point of operation of the operating means around the blank, and means for tipping the operating means during its transfer around the blank to maintain the operating means substantially normal to the blank, substantially as described.

40 17. A machine for making casting patterns, having, in combination, means for building a flange on the edge of a blank, devices for supporting and presenting the blank to the operating means, means for relatively actuating the operating means and blank to transfer the point of operation of the operating means around the blank, and a carrier for the operating means tippable during the transfer of the point of operation of the operating means around the blank to maintain the operating means substantially normal to the blank, substantially as described.

55 18. A machine for making casting patterns, having, in combination, means for building a flange on the edge of a sole-shaped blank, devices for supporting and presenting the blank to the operating means, means for relatively actuating the operating means and blank to transfer the point of operation of the operating means around the blank, and means for swinging the operating means during the transfer of the point of operation of the operating means to permit

the traverse of the operating means along 65 the reverse curves of the blank, substantially as described.

19. A machine for making casting patterns, having, in combination, means for building a flange on the edge of a blank, devices for supporting and presenting the blank to the operating means, means for relatively actuating the operating means and blank to transfer the point of operation of the operating means around the blank, 70 a carrier for the operating means tippable during the transfer of the point of operation of the operating means around the blank to maintain the operating means substantially 75 normal to the blank, and a swinging support for the carrier, substantially as described.

20. A machine for making casting patterns, having, in combination, means for building a flange on the edge of a blank, a 80 tipping carrier therefor, a swinging support for the carrier, and a rotatable support for the blank, the axes of the blank support and the carrier for the operating means being located at equal distances from 90 the axis of the carrier support, substantially as described.

21. A machine for building a flange on the edge of a blank, having, in combination, means for building a flange on the edge of 95 a blank, a blank support, means for rotating the blank support to transfer the point of operation of the operating means around the blank, a carrier for the operating means tippable during the transfer of the point of 100 operation of the operating means around the blank to maintain the operating means substantially normal to the blank, and means for supporting the axis of the tipping carrier to swing in the arc of a circle which if 105 extended will pass through the axis of the blank support, substantially as described.

22. A machine for making casting patterns, having, in combination, a support for a sole-shaped blank, and means for building a laminated flange on the peripheral edge of the blank, substantially as described.

23. A machine for making casting patterns, having, in combination, a support for a flat blank, devices for supporting and presenting a strip of material to the blank, and means for attaching the material to the edge of the blank, substantially as described.

24. A machine for making casting patterns, having, in combination, a support for 120 a flat blank, devices for supporting and presenting a strip of material to the blank, means for attaching the material to the edge of the blank, and means for relatively actuating the blank and operating means to 125 transfer the point of operation of the operating means around the blank, substantially as described.

25. A machine for making casting patterns, having, in combination, a support for a flat blank, devices for supporting and presenting a strip of material to the blank, and means for winding the strip around the peripheral edge of the blank, substantially as described. 65
- 10 26. A machine for making casting patterns, having, in combination, a support for a flat blank, devices for supporting and presenting a strip of material to the blank, operating means for attaching the material to the blank, and means for winding the strip around the blank, substantially as described. 70
- 15 27. A machine for making casting patterns, having, in combination, a support for a flat blank, devices for supporting and presenting a strip of material to the blank, operating means for attaching the material to the blank, and means for winding the strip around the blank and building the material in layers on the blank, substantially as described. 80
- 20 28. A machine for making casting patterns, having, in combination, a support for a flat blank, rolls for attaching a strip of material to the edge of the blank, and means for rotating the blank to transfer the point of operation of the rolls around the blank, substantially as described. 90
- 25 29. A machine for making casting patterns, having, in combination, a support for a flat blank, rolls for attaching a strip of material to the edge of the blank, means for rotating the blank to transfer the point of operation of the rolls around the blank, and means operating during the transfer of the point of operation of the rolls around the blank for tipping the rolls to maintain them substantially normal to the edge of the blank, substantially as described. 95
- 30 30. A machine for making casting patterns, having, in combination, a support for a flat blank, rolls for attaching a strip of material to the edge of the blank, a carrier for the rolls, and means for tipping the carrier, substantially as described. 100
- 35 31. A machine for making casting patterns, having, in combination, a support for a flat blank, rolls for attaching a strip of material to the edge of the blank, a support for the rolls, and means for swinging the support, substantially as described. 110
- 40 32. A machine for making casting patterns, having, in combination, a support for a flat blank, rolls for attaching a strip of material to the edge of the blank, a carrier for the rolls, a support for the carrier, and means for tipping the carrier and swinging the support, substantially as described. 115
- 45 33. A machine for making casting patterns, having, in combination, a support for a blank, operating means for attaching a strip of material to the edge of the blank, devices for supporting and presenting the strip of material to the operating means including a pair of rolls, and means for maintaining the operating means and blank and the pair of rolls in engagement, substantially as described. 120
- 50 34. A machine for making casting patterns, having, in combination, a support for a blank, operating means for attaching a strip of material to the edge of the blank, devices for supporting and presenting the strip of material to the operating means including a pair of rolls, means for maintaining the operating means and blank and the pair of rolls in engagement, and a single operating device for disengaging the operating means and blank and the pair of rolls, substantially as described. 125
- 55 35. A machine for making casting patterns, having, in combination, devices for supporting, guiding and feeding a strip of material, and a feed accelerator for producing slack in the strip during its feed, substantially as described. 130
- 60 36. A machine for making casting patterns, having, in combination, devices for supporting, guiding and feeding a strip of material, a feed accelerator for producing slack in the strip during its feed, and mechanism for actuating the accelerator to intermittently produce such slack in the strip during each cycle of the machine, substantially as described. 135
- 65 37. A machine for making casting patterns, having, in combination, devices for supporting, guiding and feeding a strip of material, a feed accelerator for producing slack in the strip during its feed, and mechanism for actuating the accelerator to intermittently produce such slack in the strip at regular intervals, substantially as described. 140
- 70 38. A machine for making casting patterns, having, in combination, devices for supporting, guiding and feeding a strip of material, a feed accelerator for producing slack in the strip during its feed, and mechanism for withdrawing the accelerator from the strip after an interval, substantially as described. 145
- 75 39. A machine for making casting patterns, having, in combination, devices for supporting, guiding and feeding a strip of material, a feed accelerator for producing slack in the strip during its feed, and mechanism for actuating the accelerator to intermittently produce such slack in the strip and withdraw the accelerator from the strip after an interval, substantially as described. 150
- 80 40. A machine for making casting patterns, having, in combination, devices for supporting, guiding and feeding a strip of material, means for attaching the material

to the peripheral edge of a sole-shaped blank, and a feed accelerator for producing slack in the material during its feed to permit the operating means to attach the material to the shank portions of the blank, substantially as described.

41. A machine for making casting patterns, having, in combination, devices for supporting, guiding and feeding a strip of material, means for attaching the material to the peripheral edge of a sole-shaped blank, a tipping carrier for the operating means and a feed accelerator for producing slack in the material mounted to swing about the axis of the carrier, substantially as described.

42. A machine for making casting patterns, having, in combination, devices for supporting, guiding and feeding a strip of material, means for attaching the material to the peripheral edge of a sole-shaped blank, a tipping carrier for the operating means, a feed accelerator for producing slack in the material, and means for actuating the feed accelerator to produce slack in the material when the carrier tips in one direction, substantially as described.

43. A machine for making casting patterns, having, in combination, devices for supporting, guiding and feeding a strip of material, means for attaching the material to the peripheral edge of a sole-shaped blank, a tipping carrier for the operating means, a feed accelerator for producing slack in the material, means for actuating the feed accelerator to produce slack in the material when the carrier tips in one direction, and means for withdrawing the accelerator from the strip when the carrier tips in the other direction, substantially as described.

44. A machine for making casting patterns, having, in combination, a support for a sole-shaped blank, devices for supporting and presenting a strip of material to the blank, operating means for attaching the material to the peripheral edge of the blank, means for relatively actuating the blank and operating means to transfer the point of operation of the operating means around the blank, and means actuated as the point of operation of the operating means is transferred around the ends of the blank for producing slack in the unattached material to permit the attachment of the material to the edge of the blank at the shank portions thereof, substantially as described.

45. A machine for making casting patterns, having, in combination, a support for a blank, means for applying a strip of material to the peripheral edge of the blank, means for relatively actuating the operating means and blank to transfer the point of operation of the operating means around the blank and feed the strip, and additional

means for pulling upon the source of supply of the material at intervals during the transfer of the point of operation of the operating means around the blank, substantially as described.

46. A machine for making casting patterns, having, in combination, a support for a sole-shaped blank, means for applying a strip of material to the peripheral edge of the blank, means for relatively actuating the operating means and blank to transfer the point of operation of the operating means around the blank and feed the strip, and additional means actuated as the point of operation of the operating means is transferred around the toe and heel portions of the blank for pulling upon the source of supply of the material, substantially as described.

47. A machine for making casting patterns, having, in combination, a support for a sole-shaped blank, means for applying a strip of material to the peripheral edge of the blank, means for relatively actuating the operating means and blank to transfer the point of operation of the operating means around the blank and feed the strip, additional means actuated as the point of operation of the operating means is transferred around the toe and heel portions of the blank for pulling upon the source of supply of the material, and means for causing the additional means to release the material as the point of operation of the operating means is transferred along the shank portions of the blank, substantially as described.

48. In a machine for making casting patterns, having, in combination, a driving member, a driven member carrying devices for clamping a blank to the driving member, a tension device for holding the driven member in clamping position, and a locking device for holding the driven member out of clamping position, substantially as described.

49. In a machine for making casting patterns, having, in combination, a tool carrier, a support therefor, means for moving the support to bring the tool into and out of operative position, and a locking device for holding the support with the tool in an inoperative position, substantially as described.

50. A machine for making casting patterns, having, in combination, means for laying a strip of material upon the edge of the blank, means for fixing the material laid upon the blank to form a flange thereon, and means for causing the fixing means to operate under a heavier pressure than the laying means, substantially as described.

51. A machine for making casting patterns, having, in combination, a roll for laying a strip of material upon the edge of a

blank, a second roll for fixing the material laid upon the blank to form a flange thereon, and means for causing the fixing roll to operate under a heavier pressure than the 5 laying roll, substantially as described.

52. In a machine for making casting patterns a tipping tool carrier, and a pair of rolls journaled in the carrier at different distances from the axis of the carrier, substantially as described.

53. In a machine for making casting patterns, a tipping tool carrier, and a pair of

rolls for laying and fixing respectively a strip of material upon the edge of a blank to build a flange thereon said fixing roll being 15 journaled in the carrier at a lesser distance from the axis of the carrier than the journal for the laying roll, substantially as described.

MARK E. FERNALD.
